UNITED STATES PATENT OFFICE.

FRIEND A. RUSS, OF GREENWICH, CONNECTICUT, ASSIGNOR TO ROBERT N. BASSETT COMPANY, INCORPORATED, OF SHELTON, CONNECTICUT, A CORPORATION OF CONNECTICUT.

BUCKLE.

1,338,535.

Specification of Letters Patent. Patented Apr. 27, 1920.

Application filed February 19, 1919. Serial No. 278,062.

To all whom it may concern:

Be it known that I, FRIEND A. RUSS, a citizen of the United States, residing at Greenwich, in the county of Fairfield and 5 State of Connecticut, have invented a certain new and useful Improvement in Buckles, of which the following is a specification.

My invention relates to buckles for running webbing of the class used on hose supporters, suspenders and like articles and its 10 object is to provide such buckle to which the webbing may be attached by swaging.

In order to enable my invention to be understood by persons skilled in the art, I 15 have embodied the same in a well known type of sheet metal buckle in which the lever member is pivoted to a back plate having a slot through which passes the 20 fixed end of the webbing. In such a buckle heretofore it has been customary to stitch the end of the webbing upon itself after it has been passed through the slot and in this 25 manner to form a terminal loop in the webbing which embraces a portion of the back or bar on one side of the slot. My invention consists in the provision of means for 30 eliminating the time and expense required in stitching the webbing in this manner, as will more fully appear in the buckle set forth in the following description and accompanying drawings in which like reference characters refer to corresponding parts.

In the drawings:

35 Figure 1 is a front view of my buckle, a portion of the lever and attached webbing shown broken away;

Fig. 2, a central vertical section of the buckle shown in Fig. 1, and

40 Fig. 3 an end view of the buckle before the webbing is attached thereto.

My buckle generally comprises the back A and the lever B. The back A is suitably blanked and struck up out of sheet metal to 45 form the back plate 2 having the forwardly turned side ears 3, 3 provided with apertures 4, 4. Extending transversely across the back plate 2 between the ears 3, 3 is a slot 5 having a lower edge 6. This slot is 50 of a width sufficient to enable ordinary webbing to be passed freely therethrough and the upper extremity of the metal above the slot is folded downwardly and rearwardly to form a projecting lip 7 having a free 55 edge 8, as shown in Fig. 3. The lever B is

also suitably blanked and struck up out of sheet metal to form the front portion or finger piece 9, the web engaging edge 10 and the laterally projecting trunnions 11, 11, which latter are journaled in the apertures 4, 4 in the side ears 3, 3 forming a pivotal connection between the lever and back. To web the buckle the extremity k of the webbing C is inserted rearwardly through the slot 5 in the back plate 2. The 60 lip 7 is then pressed down against the rear face of the back so that its edge 8 coöperates with the lower edge 6 of the slot 5 to securely fasten the extremity k. The extremity of the webbing being thus secured to 65 the back the moving portion is folded rearwardly over the top edge of the back, then downwardly and upwardly after which it is passed between the lever and front face portion of the back. The buckle strung in this 70 manner forms an adjustable loop in the webbing, carrying the cast-off member D. By fastening the end of the webbing between the edge of the lip and the lower edge of the slot I am enabled to dispense with the 75 stitching of the end to the back reach as is usually done in this style of buckle. I am also enabled to leave a shorter end of the webbing projecting through the slot than is required in the case of stitching, and since 80 this short end is not connected to the back reach of the webbing it permits the latter to swing away from the back face of the buckle and take a straight downward direction when the buckle is tilted, as shown, and 85 the webbing is under stress. Since the webbing gripping lip 7 is inside the folded portion of the webbing, it does not separate the moving portion, which is engaged by the lever edge, and the fixed extremity passing 90 over the front face of the back, so that the frictional surface presented by this underlying extremity to the moving portion assists in holding the latter and preventing it from slipping when the buckle is closed. 95

This is a feature which is not present in the prevailing style of buckle wherein the webbing is fastened to the front portion of the back plate by an upwardly turned lip. It is not necessary, however, that the lip 105 should be bent downwardly from the top of the back plate since it may project from other convenient portions of the buckle provided it will coöperate with the metal along one of the sides of the slot to grip the web- 110

bing passing through the slot, the broad feature of my invention being the means for fastening the webbing by swaging as it passes through a slot in contra distinction to fastening the end of the webbing between the lip and the opposite face portion of a solid back. While my novel means of fastening the webbing enables me to construct a lever buckle of the rustless type having 10 manifest merit, yet my invention is not confined to buckles of this type, since it is obvious that the slot and lip construction might be utilized to advantage in buckles, and like metal trimmings of other types for 15 running webbing, wherever desirable.

Having now described my invention, what I claim and desire to protect by Letters Patent is:

1. A buckle comprising a sheet metal plate 20 having a slot for the passage of a running webbing, the metal on one side of said slot being folded upon itself to form a lip which is arranged to coöperate with the metal on the opposite side of said slot to grip said webbing.

2. A buckle comprising a sheet metal plate having a slot for the passage of running webbing, the said plate on one side of said slot being folded on itself to form a lip the 30 edge of which is arranged to be pressed toward the opposite edge of said slot to grip said webbing.

3. A buckle comprising a sheet metal plate having an opening, the metal on one side of said opening being folded on itself to 35 form a lip, in combination with a running webbing which passes through said opening, the said webbing being gripped between the edge of said lip and one edge of said opening.

4. A lever buckle of the kind in which the back is provided with a sheet metal bar around which is folded a running webbing, characterized in that the said bar is folded on itself to form a lip between the edge of 45 which and an edge on said back is gripped the end of the webbing.

5. A buckle comprising a sheet metal back plate having forwardly turned side ears between which is journaled a pivoted lever 50 arranged to coöperate with the upper portion of said back plate, the said back plate being provided with a slot between said ears and being folded on itself on one side of said slot to form a lip, in combination with a 55 running webbing one end of which is fastened between the edge of said lip and one side of said slot, the said end being folded around said back above said slot and the opposite end being passed upwardly between 60 the lever and back.

In testimony whereof I have hereunto set my hand this 14th day of February 1919.

FRIEND A. RUSS.
